(57) **CLAIM**

We claim the ornamental design for a wet wipes dispenser, as shown and described.

DESCRIPTION

FIG. 1 is a perspective view of a wet wipes dispenser showing our new design.

FIG. 2 is a front view thereof.

FIG. 3 is a top view thereof.

FIG. 4 is a left side view thereof; and,

FIG. 5 is a front view thereof; with lid of the wet wipes dispenser rotated into an open usage condition.

The broken line portion of the figure drawings is included so show unclaimed subject matter only and forms no part of the claimed design.

1 Claim, 5 Drawing Sheets
